UNITED STATES PATENT OFFICE

154,373

DESIGN FOR A HANDBAG

Charles Feigl, New York, N. Y.

Application September 10, 1948, Serial No. 148,527

Term of patent 3½ years

(Cl. D87—3)

To all whom it may concern:

Be it known that I, Charles Feigl, a citizen of the United States of America, residing in New York city, county of New York, and State of New York, have invented a new, original, and ornamental Design for a Handbag, of which the following is a specification, reference being had to the accompanying drawing, forming part thereof, wherein,

I claim:

The ornamental design for a handbag, substantially as shown and described.

CHARLES FEIGL.
